GASFILLED INCANDESCENT CATHODE
DISCHARGE TUBE

Gilles Holst, Eindhoven, Netherlands, assignor to
N. V. Philips' Gloeilampenfabrieken, Eindhoven, Netherlands, a limited-liability company of the Netherlands

Application April 5, 1928, Serial No. 267,623,
and in the Netherlands April 11, 1927

13 Claims. (Cl. 175—363)

This invention relates to an electrical device, more particularly adapted for use in rectifying alternating currents, in which an incandescent cathode discharge tube is used. During the operation of discharge tubes of this kind the voltage between the electrodes is determined by the voltage drop between the incandescent cathode and a point lying close to the anode and by the anode drop. The latter is produced in a gas discharge owing to a deficiency of positive ions in the immediate vicinity of the anode. The invention has for its object to provide suitable means for reducing the voltage drop and consequently the operating voltage of the discharge tube.

According to the invention, this result is obtained by arranging in the discharge tube employing an auxiliary electron-emitting cathode, and by connecting this cathode to a point in the circuit in such way that a discharge appears between this cathode and the anode in the neighborhood in which it is placed. The auxiliary discharge produced between the auxiliary cathode and the anode furnishes sufficient positive ions to neutralize the anode drop to a large extent. In order to limit as much as possible the loss of energy caused by the auxiliary discharge, a resistance may be connected between the auxiliary cathode and the anode, said resistance serving to limit to a minimum the current flowing between the auxiliary cathode and the anode. The invention affords special advantages with discharge tubes of the said kind for great current intensities, as with such discharge tubes, due to the neutralization of the anode drop, the loss of energy in the discharge is diminished by an amount almost equal to the product of the anode drop and the current intensity.

Gas filled discharge tubes for illuminating purposes are known already in which at each end of the tube, an anode is arranged, surrounding an electron emitting cathode. In such case the cathode is directly connected electrically to the surrounding anode, so that no discharge between these electrodes is produced. The object of this construction is to permit the current to pass in both directions with the same ease.

A discharge tube used in a device according to the invention has the characteristic feature that the electron emitting auxiliary cathode is insulated from the anode. Preferably the electron emitting cathode is an incandescent cathode. In an exceptionally suitable mode of construction the cathode is arranged within a hollow body, the anode being placed before an open end of this

body and insulated therefrom. It is clear that in this case the hollow body forces the ions to remain in the neighborhood of the anode. To leave the hollow body they must pass the anode. By forming the hollow body of metal and providing it with a pole wire, a potential differing from that of the anode may be given to the body, in order to further direct the ions to the anode. The anode may be perforated in suitable manner; for instance, it may be made of gauze, to enable the positive ions produced by the auxiliary discharge to enter easily into the main discharge path.

The invention will be more clearly understood by referring to the accompanying drawing which represents, by way of example, a discharge tube included in a circuit arrangement for the rectifying of alternating current.

The discharge tube 1 comprises an incandescent cathode 2 and an anode 3. An auxiliary incandescent cathode 4 is arranged behind the anode 3 in the interior of the hollow body 5 which forms one structure with the anode 3 but is electrically insulated therefrom. The anode may consist of a gauze or perforated wall which allows positive ions produced by the auxiliary discharge to enter into the main-discharge path. The cathode 2 is connected to one end of the secondary 6 of a transformer the primary of which is not illustrated. The other end of the secondary winding is connected to the anode 3. The cathode 2 and the auxiliary cathode 4 are brought up to the required temperature by current supplied from transformer windings 7 and 8. The auxiliary cathode 4 is connected to an intermediate point of the secondary 6 so that between the electrodes 4 and 3 there is only a comparatively small potential difference. The hollow body 5 which is electrically insulated from the anode, may be brought to the required potential by means of a connection 9.

As the body 5 is to direct the positive ions from the auxiliary cathode 4 to the anode 3, its potential must be higher than that of the cathode 4. As a rule, it suffices that the potential of the member 5 be but a few volts higher than the potential of cathode 4, although under circumstances it may be even higher than the potential of the anode 3.

To obtain the proper potential for the body 5, the lead 9 may be connected to a tap of the transformer winding 6 which lies between the left hand terminal of the transformer and that point to which the cathode 4 is connected. Or a storage battery may be connected between the body

95

100

110

5 and the auxiliary cathode 4. In both of these cases an alternating potential is applied to the body 5.

5 If it is desired to apply a direct potential to the body 5, the lead 9 is connected through a battery to the middle point of the secondary winding of transformer 8.

10 In any case, it is preferable to limit the current flow between the body 5 and the cathode 4 by providing a resistance in the circuit branch leading to the body 5.

15 The battery potential in the above cases is preferably of the order of 8 to 10 volts.

What I claim is:

16 1. An electric discharge device comprising a gasfilled envelope, an anode, and an incandescent cathode therein, means to neutralize the anode drop, said means comprising an auxiliary incandescent cathode disposed in the vicinity of the anode, and insulated therefrom, said auxiliary cathode having an electron emission of such magnitude to produce an auxiliary discharge between said auxiliary cathode and said anode to furnish a sufficient number of positive ions to neutralize the anode drop.

20 2. An electric discharge device comprising a gasfilled envelope, and anode, and an incandescent cathode therein, means to neutralize the anode drop, said means comprising an auxiliary incandescent cathode on the far side of the anode from the main cathode and having an electron emission of sufficient magnitude to produce an auxiliary discharge between said auxiliary cathode and said anode to furnish a sufficient number of positive ions to neutralize the anode drop.

25 3. An electric discharge device comprising a gasfilled envelope, an anode, and an incandescent cathode therein, means to neutralize the anode drop, said means comprising an auxiliary incandescent cathode spaced from said anode at a distance shorter than that between the main cathode and the anode, and a screen on the far side of the auxiliary cathode from the anode, and having a lead wire sealed through the envelope.

30 4. An electric discharge device comprising an envelope, an incandescent cathode, an auxiliary cathode, a open-ended, hollow metal body surrounding the auxiliary cathode, a perforated anode disposed in front of the open end of the hollow body and insulated therefrom as well as from the other electrodes, and a lead wire from said body sealed through said envelope, said electrodes being disposed in said envelope.

35 5. In combination an electrical discharge device, comprising a sealed gasfilled envelope, an anode, an incandescent main cathode, and an auxiliary cathode therein, said auxiliary cathode being disposed at a shorter distance from the anode than the main cathode, and a source of electric supply connected to the electrodes for causing current flow between the main cathode and the anode and between the auxiliary cathode and the anode, the last-mentioned current having a value sufficient to produce ions substantially neutralizing the anode drop of the discharge between the main electrodes.

40 6. In combination, for rectifying alternating currents, an electrical discharge device, comprising a gasfilled, sealed envelope, an anode, an incandescent main cathode, and an auxilliary cathode therein, said auxiliary cathode being disposed at a shorter distance from the anode than the main cathode, and a circuit comprising

45 a source of electric supply across the main cathode and the anode, and across the anode and auxiliary cathode, and means for limiting the current transmitted between the anode and the auxiliary cathode to a value at which the number of positive ions is sufficient to substantially neutralize the anode drop of the discharge between the main electrodes.

50 7. In combination, an electric discharge device comprising an anode, an incandescent cathode, an auxiliary incandescent cathode in the vicinity of the anode, a gasfilled envelope for the electrodes and a circuit comprising an electric supply source, and means by which current is transferred between the main cathode and the anode and between the auxiliary cathode and the anode, the last-mentioned current having a value sufficient to provide for ions substantially neutralizing the anode drop of the discharge between the main electrodes.

55 8. In combination, an electric discharge device comprising a gasfilled envelope, an anode, an incandescent cathode, and an auxiliary incandescent cathode in the vicinity of the anode disposed in said envelope, and a circuit comprising an electric supply source and a transformer connected to said supply source and provided with secondary winding by which current is transferred between the main cathode and the anode and between the auxiliary cathode and the anode, the last-mentioned current having a value sufficient to provide for ions substantially neutralizing the anode drop of the discharge between the main electrodes.

60 9. In combination, an electrical discharge device, for rectifying alternating currents comprising a sealed gasfilled envelope, a main cathode, and an auxiliary cathode in said envelope, said auxiliary cathode being disposed at a shorter distance from the anode than the main cathode, and a circuit, comprising an electric supply source, means by which current is transferred between the main cathode and the anode, and a resistance in circuit with the auxiliary cathode and the anode for limiting the current transmitted between the anode and the auxiliary cathode to a value at which a sufficient number of positive ions are furnished to substantially neutralize the anode drop of the discharge between the main electrodes.

65 10. The combination of an electric discharge device comprising a gasfilled envelope, an anode, an incandescent cathode, and an auxiliary incandescent cathode therein, said auxiliary cathode being disposed in the vicinity of the anode, a screen on the far side of the auxiliary cathode from the anode, an electric supply source, means by which current is transferred from said supply source between the main cathode and the anode and between the auxiliary cathode and the anode, means to provide the screen with a potential of such value that a sufficient number of positive ions furnished by the current between the auxiliary cathode and the anode, are driven into the discharge path between the main cathode and the anode to neutralize the anode drop of the main discharge.

70 11. A gasfilled incandescent cathode discharge tube adapted to be used in a device for rectifying alternating currents, comprising an envelope, an open ended hollow body of electrically conductive material therein, a main cathode, an incandescent electron emitting auxiliary cathode arranged within said hollow body, and an anode

placed before the open end of said body and insulated therefrom.

12. A gasfilled incandescent cathode discharge tube adapted to be used in a device for rectifying alternating currents, comprising an envelope, an open ended hollow body of electrically conductive material therein, a main cathode, an electron emitting incandescent auxiliary cathode arranged within said hollow metal body, a lead for said body sealed through said envelope, and a perforated anode placed before the open end of said body and insulated therefrom.

10 said body sealed through said envelope, the anode being placed before the open end of this body and insulated therefrom.

13. A gasfilled incandescent cathode discharge tube adapted to be used in a device for rectifying alternating currents, comprising an envelope, an open ended hollow body of electrically conductive material therein, a main cathode, an electron emitting incandescent auxiliary cathode arranged within said hollow metal body, a lead for said body sealed through said envelope, and a perforated anode placed before the open end of said body and insulated therefrom.
